Emmet Goldsborough,
ATTORNEY.

UNITED STATES PATENT OFFICE.

JOHN W. PRIDMORE, OF CHICAGO, ILLINOIS, ASSIGNOR TO THE McCORMICK HARVESTING MACHINE COMPANY, OF SAME PLACE.

GRAIN-BINDER.

SPECIFICATION forming part of Letters Patent No. 651,770, dated June 12, 1900.

Application filed June 19, 1899. Serial No. 721,066. (No model.)

To all whom it may concern:

Be it known that I, JOHN W. PRIDMORE, a citizen of the United States, residing at Chicago, in the county of Cook and State of Illinois, have invented certain new and useful Improvements in Grain-Binders; and I do hereby declare the following to be a full, clear, and exact description of the invention, such as will enable others skilled in the art to which it appertains to make and use the same.

The improvement has reference to grain-binders in general, but more especially to a type that are now well known and wherein the knotter-operating shaft is intermittently driven from the continuously-running packer-shaft through the intermediacy of a vertical shaft having a miter-gear connection at its upper end with a drive-wheel on the shaft. An example of this type is embraced in the patent granted to the McCormick Harvesting Machine Company, assignee of Henry E. Pridmore, March 29, 1898, No. 601,609, and the present improvement is herein illustrated and described as applied to the machine of that patent, though without intending thereby to restrict its application to that or any other class of machines. In the operation of these machines in the field there is a tendency, due to the high speed at which the binder mechanism is run, as well as the constant jolting and jarring of the machine, for the trip-stop to rebound on being returned into the path of the revolving trip-dog as the bundle is being ejected, and as this dog revolves very rapidly the result is that the binder-mechanism is not thrown out of action at the completion of each bundle, as it should be, and the binding operation is immediately repeated before sufficient grain has accumulated to form another bundle. It is the object of my invention to prevent this rebound of the trip-stop by holding it down until the trip-dog has struck it and disengaged the shaft which drives the knotter-shaft; and the invention consists, broadly, in arranging a projection or part of the drive-wheel of the knotter-operating shaft in such relation to the parts connected with the trip-stop that at the appropriate point in the revolution of the wheel it will strike an arm connected with the stop and hold it down just long enough

for the revolving dog to hit it and unclutch the binder.

The invention also includes certain specific arrangements of parts whereby the improvement has been adapted to the machine of the patent above referred to.

In the accompanying drawings, Figure 1 is an end view of so much of the binder-operating mechanism as is necessary to an understanding of the above-described improvement. Fig. 2 is a side view thereof, the horizontal members of the binder-frame being broken off; and Fig. 3 is a sectional detail of the lower end of the lever for operating the trip-stop.

Referring to the views, A denotes the overhead tubular arm of the binder-frame, D the corresponding member of the frame underneath the binder-deck, and E the vertical member joining these two arms together and preferably forming a housing for the vertical shaft by means of which the wheel B of the knotter-operating shaft C is driven from a pinion on the continuously-running packer-shaft. The wheel B is driven by a pinion on the upper end of the vertical shaft, as in the above-referred-to patent, and on the lower end of the shaft there is the same pinion E', clutch-box e², and connecting-sleeve e. The clutch-trip-dog J is also the same as in the above-mentioned patent, as well as the manner in which it connects and disconnects the clutch-box from the shaft.

The needle-shaft is denoted at G, and the arm I and link H constitute the means whereby the needle is given the proper reciprocation by the wheel of the knotter-operating shaft C.

K denotes the trip-finger, and K' its shaft. On the end of the shaft K' there is secured the stop-arm K², the construction and manner of operating which are the same as in the previously-patented machine.

The trip-stop is denoted by K³. It is simply a projection on the outer end of the stop-arm K², and as the arm rises and falls it is thrown into and out of the path of rotation of the trip-dog J in a manner now well understood. The lever for operating the stop-arm is shown at L. It is substantially the same as the lever of the above-mentioned patent

and has a roller l^3 on its upper end running in a cam-race l^2 on the wheel B. The lever carries a slide D, and on the lower end of the slide there is a pin l^5 , carrying a roller l' , which as the arm L is vibrated on its pivot l works to and fro in a cam-slot l^6 in the stop-arm K².

The slide D is pressed downwardly on the lever L by means of a strong spring D², which reacts between a projection l^4 at the lower end of the slide and an abutment on the lever or binder-frame above. The object of allowing the part D to slide and holding it down by spring-pressure is to permit the trip-finger K to yield against the pressure of the grain and rock the shaft K', so as to raise the stop-arm K² and release the dog J; also, so as to compress the bundle with a yielding pressure when after the binder is started the lever L lowers the arm K² and presses the trip-finger upwardly against the outer side of the bundle.

It will be understood that the operations of applying the band, compressing the bundle, tying the knot, and ejecting the bundle all take place during and are caused by a single cycle or revolution of the wheel B. Although the action of this wheel is intermittent, it rotates with considerable speed, and the stop-arm K² comes down suddenly just before the wheel completes its cycle and reaches the point of rest, where it awaits the next binding operation. The stop-arm K² is quite long, and a very slight movement of its inner end suffices to throw the stop K³ at its outer end up out of reach of the dog J, and the force and speed with which the arm K² is thrown down and the jarring and jolting of the whole machine are such that occasionally there is just enough rebound of the arm to lift the stop and let the dog continue its revolution, with the result already explained. I have discovered, however, that the wheel B may be made to hold the arm down and prevent this rebound, and for this purpose I have provided the slide D with an upwardly-extending arm D³ which projects into proximity to the periphery of the wheel B, and at the outer end of this arm I arrange a cam or wiper d. With this construction any rebound of the stop-arm would of course cause the arm D³ to fly up, and at such point on the periphery of the wheel B as that it would be struck by the cam d should the arm D³ rebound in this way I provide a short cam or wiper b, and at the appropriate point in the revolution of the wheel B the two cams b and d come together, with the result that the slide D is prevented from flying up by a positive abutment so long as the two cams are in contact.

It would of course not do to have the wheel B stop with its projection b over the end of the arm D³, for the reason that the slide D must move upward slightly in order that the trip-finger may lift the stop K³ and release the dog J; nor does the rebound of the arm K² occur after the wheel has come to rest,

but just before it completes its cycle or revolution. I therefore locate the projection b on the wheel and the wiper d on the arm D³ so that they will meet just before the wheel reaches the end of its rotation and proportion the extent of the coöperating surfaces, so that the remaining movement of the wheel after they have come together will just cause them to clear each other, so as to leave the parts in a position to be tripped as usual. This position is indicated in dotted lines s in Fig. 1, and the dotted lines in the lower part of the figure illustrate the movement of the trip-finger, the stop-arm, and the slide D incident to setting the binder into operation.

Having thus described my invention, what I claim, and desire to secure, is

1. In a grain-binder, the combination with a trip-finger carried by a rock-shaft independent of the needle-shaft, of a trip-stop carried by the rock-shaft, and an arm connected with said stop and coöperating with the knotter-operating wheel to prevent the rebound of the parts as the wheel completes a cycle from throwing the stop out of the path of the trip-dog.

2. In a grain-binder, the combination with the trip-finger and its shaft, of a trip-stop carried by the shaft, a lever for moving the stop into the path of the trip-dog and an arm connected with said lever and projecting into such proximity to the knotter-operating wheel as to coöperate therewith to prevent the rebound of the parts as the wheel completes a cycle from throwing the stop out of the path of the trip-dog.

3. In a grain-binder, the combination with the trip-finger and its shaft, of a trip-stop carried by the shaft, a pivoted lever acting on the stop to cause the finger to compress the bundle, an arm connected with the lever, and a projection on the knotter-operating wheel to prevent the rebound of the parts as the wheel completes a cycle from throwing the stop out of the path of the trip-dog.

4. In a grain-binder, the combination with the trip-finger and its shaft, of a trip-stop carried by the shaft, a pivoted lever actuated by the knotter-operating wheel to compress the bundle with the trip-finger, an arm connected with said lever and projecting into proximity to the knotter-operating wheel, and a projection thereon coöperating with the arm at the appropriate point in the revolution of the wheel to prevent the rebound of the parts as the wheel completes a cycle from throwing the stop out of the path of the trip-dog.

5. In a grain-binder, the combination with the trip-finger and its shaft, of a trip-stop carried by the shaft, a pivoted lever actuated by the knotter-operating wheel to compress the bundle with the trip-finger, and a spring-pressed slide on the lever engaging the trip-stop, said slide having an arm projecting into such proximity to the knotter-operating wheel as to coöperate therewith and prevent the re-

bound of the parts as the wheel completes a cycle from throwing the stop out of the path of the trip-dog.

6. In a grain-binder, the combination with 5 the trip-finger and its shaft, of a trip-stop carried by the shaft, a pivoted lever actuated by the knotter-operating wheel, a spring-pressed slide carried by said lever, a roller on the slide working in a slot in the trip-stop 10 to cause the trip-finger to compress the bundle as the lever is actuated, a projection on the knotter-operating wheel, and an arm pro-

jecting from the slide on the lever into such proximity to the wheel that it co-operates with the projection to prevent the rebound of the 15 parts as the wheel completes a cycle from throwing the stop out of the path of the trip-dog.

In testimony whereof I affix my signature in presence of two witnesses.

JOHN W. PRIDMORE.
